RESILIENT WHEEL

Filed Aug. 9, 1920

Fig. 1.

Fig. 2.

UNITED STATES PATENT OFFICE.

JOSEF RITTMAYER, OF CHICAGO, AND PETER J. GEIMAN, OF HARVEY, ILLINOIS.

RESILIENT WHEEL.

Application filed August 9, 1920. Serial No. 402,090.

To all whom it may concern:

Be it known that we, JOSEF RITTMAYER, a citizen of the United States, and a resident of the city of Chicago, in the county of Cook and State of Illinois, and PETER J. GEIMAN, a citizen of the United States, and a resident of Harvey, in the county of Cook and State of Illinois, have invented certain new and useful Improvements in 10 Resilient Wheels, of which the following is a specification.

Our invention relates to resilient wheels, and particularly to those of the type in which the hub and felloe are connected by 15 means of a multiplicity of curved spring members.

The object thereof is to provide a substantial and durable wheel of simple construction, in which the several spring members 20 are co-ordinated and held in co-acting relation throughout the area of their operation. It is a further object thereof to so enclose the area of said spring operation that the 25 springs will be concealed from view and also that the enclosure therefor will not be invaded by dust or mud.

The principles of our invention are illustrated in the drawings, in which—

Fig. 1 shows a side elevation of our improved wheel, certain portions being broken away;

Fig. 2 is a vertical section on the line 2—2 of Fig. 1.

Fig. 3 is an enlarged section showing a 35 spring spacing device; and

Fig. 4 is an enlarged side view of a securing clip.

Further describing our invention with reference to the drawings, in which like 40 characters of reference denote like parts throughout:

1 is a hub of our improved wheel, provided with annular flanges 2, and having the supporting core member 3, by which it 45 may be secured to the axle of the vehicle in the ordinary manner. 5 is a felloe, provided with a rim 6, having the retaining flanges 7, for the tire 8. In the space between the hub flanges 2 are secured a suitable number of springs 10^a, 10^b, etc. Each 50 of said springs is provided with an eye by which it is attached by a bolt 12, passing therethrough, to the hub 1 between the flanges 2. Each spring should be compounded and strengthened as desired and 55 in accordance with the use to which the

wheel is to be devoted by added leaves 13 secured by clamps or bands 14. Said springs are given the curve of a section of a spiral, and are of such length that they 60 subtend an arc of about 280 degrees. The felloe ends of the springs are attached to the felloe by clips, which may comprehend body portions 15^a, 15^b, etc., and retaining members 16^a, 16^b, etc., which are arched to 65 embrace the springs. Said body portions are seated in suitable recesses of the felloe so as to be flush throughout and are secured in place by bolts 17, which also, as herein-after explained, may perform a further office of holding an enclosing protecting disc. 70 Each of said clips is adapted to receive and hold in relative position two of the springs described. Taking for instance spring designated as 10^b: Its principal point of felloe attachment is approximately 220 degrees from the point at which it is attached to the hub. It is provided with a notch 18 formed by bending the spring and is received at the notched point in the retaining 75 member 16^b of clip 15^b. The felloe end of said spring extends beyond the clip 15^b and is received in clip 16^a below the notched portion of spring 10^b which it supports and locks therein. In like manner the notched 80 portion is held in place and supported by the end of spring 10^a. It will be thus seen that each spring is positively attached to the felloe and, at such point of attachment, is associated with the spring in rear thereof 85 while it extends forwardly to an association with the spring in advance thereof.

As a further means of co-ordinating the action of the springs and as a support therefor, we provide buffer springs 20 and eyes 90 or clips 21 which are placed at suitable points between the points of attachment to the hub and felloe. The said eyes or clips have the double function of reinforcing clips by which the leaves or laminations 95 which constitute each individual spring are held in relation to each other, and of retaining pieces to which the ends of the helical springs are attached. Said helicals are so placed with reference to the wheel as a 100 whole that their longitudinal axes are approximately in line with corresponding radii of the wheel. They thus directly reinforce the wheel and sustain the load thereon both under suspension and compression. 105

In order that the mechanism described may be enclosed both for appearance and

for protection from dust, mud and the elements, we provide an enclosing device therefor. This consists of annular discs 25, having their peripheries contacting with the 5 rim 6, and secured to the felloe by means of bolts 17, which may also be used as the means by which the spring holding clips 15 are secured to the felloe. Flanged discs 27 may be secured to the hub flanges by means 10 of bolts 12, which may also be the means by which the inner ends of the springs are secured between said flanges. The edge of disc 27 overlaps the inner edge of the annular disc 25 and it is given such off-set at 15 28 that the annular disc 25 may have movement in the space formed between the hub flanges and the off-set portion of disc 27.

We have described our invention by reference to a practical and operative example 20 thereof. We are not to be limited to the exact form of construction shown, but claim:

1. In a resilient wheel the combination of 25 a hub, a felloe, spring spokes each having a plurality of leaves curved to form a substantially uniformly developed spiral to connect said hub and felloe, clips embracing the said leaves to hold them in relation to each other, helical springs having their ends connected to adjacent clips so that the longitudinal axes of said helicals will substantially conform to the radial line of the 30 wheel.

2. In a resilient wheel, a hub, a felloe, and a multiplicity of arcuate spring spokes 35 each pivoted at one end to the hub and each continued to a point of attachment to the felloe a substantial distance beyond its point of attachment to the hub, and having its felloe end continued to and secured at the 40 point of felloe attachment of the spring spoke next preceding.

3. In a resilient wheel, a hub, a felloe provided with spoke attaching clips, and a multiplicity of arcuate spring spokes each 45 pivoted at one end to said hub and each of said spokes secured at the other end to the

felloe by one of said attaching clips and having its felloe end continued to and further secured by the attaching clip of the spring spoke next preceding.

4. In a resilient wheel, a hub, a felloe provided with spoke attaching clips, a multiplicity of arcuate spring spokes each attached at one end to said hub and provided with notches at the felloe ends, said felloe ends each being received within a felloe clip approximately 220 degrees from the point of the hub attachment, and further secured in said clip by the prolonged end of the spoke immediately in the rear thereof.

5. In a resilient wheel, a hub, a felloe, spoke attaching clips on the felloe spaced at equal distances from each other, a multiplicity of arcuate spring spokes each attached at one end to said hub and provided with notches at the felloe ends, said felloe ends being received at the notched part thereof within a felloe clip and further non-rigidly supported in said clip by the prolonged end of the spoke immediately in 70 the rear thereof.

6. In a resilient wheel, a hub, a felloe, a multiplicity of spring spokes each attached to the hub and extended therearound to a point of principal felloe attachment on the 75 opposite side of the wheel, said spokes being provided with notches at said point of principal felloe attachment, and clips on the felloe at such point of felloe attachment to receive the said spokes at the notched portion thereof, the end of each of said spokes being extended beyond said notched portion to and received by the principal attaching clip of the next preceding spring spoke to support the said preceding spoke and hold 85 it in its principal attaching clip.

In testimony whereof, we have hereunto subscribed our names, this 4th day of August 1920.

JOSEF RITTMAYER.
PETER J. GEIMAN.
